Term of patent 14 years

(Cl. D56—4)

Fig. 5

Fig. 6

FIGURE 1 is a left side, top and front perspective view of a cabinet for a stereo reproducer or similar article, showing our new design with a top cover in a raised position;

FIGURE 2 is a top plan view, to a reduced scale;

FIGURE 3 is a right side elevational view, to a reduced scale;

FIGURE 4 is a fragmentary front elevational view thereof, to an enlarged scale, showing in detail one-quarter of one of the four symmetrical ornaments centered on the speaker grilles, the remaining three-quarters being mirror-images of the quarter shown within the broken lines indicated;

FIGURE 5 is an enlarged fragmentary cross-sectional view along a line designated as 5-5 in FIGURE 1; and

FIGURE 6 is an enlarged fragmentary cross-sectional view of one of the knobs and its attachment to the door.

We claim:

The ornamental design for a cabinet for a stereo reproducer or similar article, as shown.
